UNITED STATES PATENT OFFICE.

CAROLINE VROOMAN, OF BOSTON, MASSACHUSETTS, ADMINISTRATRIX OF HENRY S. VROOMAN, DECEASED.

IMPROVEMENT IN SOLE-CHANNELING MACHINES.

Specification forming part of Letters Patent No. 139,637, dated June 3, 1873; application filed March 8, 1873.

To all whom it may concern:

Be it known that HENRY S. VROOMAN, deceased, late of Boston, in the county of Suffolk and State of Massachusetts, did invent a new and useful Improvement in Sole-Channeling Machine, of which the following is a specification:

The invention consists in the improvement of machines for channeling the soles of boots and shoes, as hereinafter described and pointed out in the claim.

In the accompanying drawing, Figure 1 is a sectional side elevation on the line $x x$ of Fig. 3. Fig. 2 is a vertical section of Fig. 3 taken on the line $y y$. Fig. 3 is a sectional top view. Fig. 4 is a view of the under side of the machine. Fig. 5 is a detail, showing the adjusting device on the swinging arm. Fig. 6 is a section of Fig. 5 taken on the line $z z$.

Similar letters of reference indicate corresponding parts.

A is the platform or bed, which is elevated on the legs B to a convenient height. C is the pattern upon which the leather sole is laid to be channelled. This pattern approximates nearly to the shape of the sole, so that soles varying somewhat in size and shape may be channelled on the same pattern; but a number of patterns are employed for the various sizes and shapes of soles, all made in the same manner and operated by the same means. The edge of the pattern is a cogged rack, D, which gears with the small spur-wheels E E, as seen in Fig. 3. This rack is held in gear by means of a roll, F, which bears against its inside. The roll revolves on a pin in the slide G, which is forced up by the spiral spring H on the shaft I. (See Fig. 2.) The wheels E E are revolved by means of the bevel-gears J and crank and shaft K K'. For the removal of the pattern the roll and slide are forced back by means of the lever L. M is a movable arm which projects over the bed, and is connected with a vertical post, N, which turns in the edge of the bed and the supporting-

lug O, so as to move the arm laterally. The post and arm are held in position by the spiral spring P. Q is a lever on the side of the arm, whose fulcrum is at R. Its back end is jointed to a rod which passes down through the hollow post N, upon the lower end of which rod is the cam-lever S. T is a spiral spring around this rod, which bears upward with a constant pressure, but is forced downward by means of the cam-lever S. U is a roller on the front end of the lever Q. This roller bears upon the sole and keeps it down firm on the pattern. Attached to the back of the movable arm M, by means of a hinge, is the adjustable guide V, which is forced outward from the arm by a spiral spring, as seen in Fig. 5. The position of this guide is regulated by the thumb-nut W. The guide bears against the edge of the sole as the pattern is revolved. The arm M, with this guide attached, is made to swing laterally by means of the lever X, which is fastened to the post N.

A cord, which passes over a pulley, is attached to this lever, and is connected to a treadle, so that by the pressure of the foot the arm is swung back for the removal of the pattern and placing the sole.

Y represents the knife or channeler, back of which is the groover Z, which is adjustably attached to the end of the lever Q. The knife and groover partake of the movement of the roller U, and are raised and lowered by means of the cam-lever S.

To operate with the machine, press down on the lever S, which lifts the knife and groover and roll U. Then, by pressing with the foot on the treadle, the arm M is swung back, or to one side. Now, place the sole on the pattern and release the treadle, which allows the guide V to press the sole. Then lift the lever S, which throws down the roll and knife, and by turning the crank the sole is revolved, and the channeling is completed.

The top of the pattern is cross-serrated, with spurs therein to hold the sole. When

the sole is placed on the pattern, the operation of channeling it is but the work of a moment, two or three turns of the crank only being sufficient.

Having thus described this invention, I claim as new and desire to secure by Letters Patent—

The combination, in a sole-channeling ma-

chine, of the swinging arm M, lever Q, roll U, pattern D, and bed A, as and for the purpose described.

CAROLINE VROOMAN,
Administratrix.
